RETAINING MEANS FOR BADGES,
BROOCHES, ORNAMENTS, BARS FOR
DECORATIVE RIBBONS, OR THE LIKE

Arthur Wakefield Madger, Malden, England

Application August 21, 1943, Serial No. 499,585
In Great Britain July 22, 1943

7 Claims. (Cl. 24—87)

This invention relates to a retaining means for badges, brooches, ornaments, bars for decorative ribbons or the like as worn upon articles of clothing and has in view to provide a means which will securely hold such a badge or like article by a locking effect obtained in conjunction with fastening pins adapted to be passed through a garment or the like thereby to prevent the possibility of accidental loss or theft of the article, the said means being capable of easy and quick manipulation and of a form such that there will be no risk of same becoming released accidentally.

The invention resides in a method of retaining badges, brooches, bars for decorative ribbons and the like fitted on to wearing apparel and the like, involving the use of pins hingedly mounted on the back of the badge or the like and adapted to be swung away from said badge or the like to allow said pins to be passed through the clothing and to be swung down towards said badge or the like to hold same in position, the said method consisting in flexing a springy locking strip to bowed form and passing the respective ends thereof beneath portions of said pins which have been passed through and are disposed behind the clothing or the like whilst the intermediate portion of said locking strip overlies extension portions of said pins, and releasing said locking strip so that same takes up a substantially flat condition and maintains the pins in their folded down positions.

The means provided according to the invention comprises a pair of spaced-apart cranked pins hingedly mounted on the back of said article and adapted when swung away from said article to be passed through a garment or the like and thereafter to be swung down towards said badge or the like, and a springy locking strip so formed or dimensioned that by flexing said strip to bowed form and then releasing same, end portions of said strip are adapted to engage beneath portions of said cranked pins whilst the intermediate portion of the strip overlies the remaining outer portions of the cranked pins, the locking strip being adapted to assume a substantially flat condition behind the garment or the like.

Preferably means is provided for locating the locking strip against endwise displacement when same is in locking position, and conveniently for this purpose the locking strip may be formed with offset portions providing shoulders adapted to abut those portions of the pins which overlie the locking strip.

Retaining devices of convenient forms in ac-

cordance with the invention are illustrated in the accompanying drawings, wherein:

Figure 1 is a perspective rear view of a ribbon-display bar having pins formed according to one embodiment of the invention, and

Figure 2 is a perspective rear view of the springy locking strip provided for use in conjunction with said pins.

Figure 3 is a perspective rear view of a piece of clothing showing the device applied thereto,

Figure 4 is a longitudinal section showing the manner of engaging the locking strip after having engaged the pins with the piece of clothing,

Figure 5 is a view similar to Figure 4 showing the position taken up by the locking strip when released to take up its locking position,

Figures 6 and 7 are views corresponding to Figures 1 and 2 showing a modification, and

Figures 8 and 9 are views corresponding to Figures 1 and 2 and showing another modification.

The device illustrated comprises a substantially rigid bar 10 adapted to be covered with decorative ribbon and to be worn upon the person, said bar being provided on the back with a pair of pins 11 which are spaced apart and hingedly mounted as at 12 so as to be capable of swinging towards and away from one another.

Each of the pins 11 is cranked to have a laterally-extending portion 13 disposed substantially parallel to the axis of the hinge and an outer portion 14 disposed at an acute angle with respect to portion 13, so that the pin has approximately the form of the numeral seven. The laterally-extending portions 13 of the pins are mutually parallel.

That is to say, the pin 11 includes a shank portion 13—14, the former being provided with an offset pintle 11a which fits into appropriate holding means 12 on the back of the article 10, and the portion 13 of the shank of the pin is cranked laterally with respect to the garment piercing arm 14. Thus the end portions 16 of the locking strip 15 may pass beneath the cranked portions 13 so that the shoulders 17 of the strip will engage the sides of the said cranked portions, as shown.

The device comprises also a separate part 15 in the form of a strip of springy material which, by its inherent spring property assumes when free a bowed shape as shown in Figure 2. At its respective ends said strip is formed with offset portions 16 connected to the main portion of the strip by shoulder portions 17, the offsetting of said portions being on the salient side of the

bowed main part. The distance between the two shoulder portions 17 of the strip 15 when said strip is maintained in a substantially straight condition is slightly less than the space that exists between the portions 13 of the respective pins 11 when said pins are swung inwardly towards one another and downwardly as far as possible.

The construction as above described is such as to enable the device to be applied to a garment in the manner now to be described.

The pins 11 are swung upwardly about their hinges 12 so as to project out from the bar 10 and the portions 14 are pushed through the garment 18, the device being manipulated to thread the portions 13 also through the garment. The angular disposition of the pins when they pierce the garment 18 is such that when the pins have been threaded through the latter to the ultimate extent, the garment has a flat condition behind the bar 10. The pins 11 are now swung down as far as possible so that the extremities of the outer portions 14 bed upon the back of the garment 18. The locking strip 15 is now taken and flexed beyond a straight condition so as to take up a bowed form reverse to that of its normal condition and as shown in Figure 4. This reduces the effective length of said locking strip so that the distance between the extremities of the end portions 16 is less than the distance between the laterally-extending portions 13 of the pins. The strip 15 is then allowed to exert itself whilst so holding same that its end portions 16 will pass beneath the respective pin portions 13. The said strip 15, in regaining or attempting to regain its original bowed form, bears upon the cranked portions 14 of the pins. The shoulder portions 17 of the strip 15 are adapted to serve as abutments which, by contact with the pin portions 13, will serve to locate the said strip by preventing it passing endwise out of its proper locking position. As shown, the locking strip extends in a straight line from one pin to the other.

Whilst the device is in its locked condition as shown in Figures 3 and 5, accidental detachment of the badge or the like and attempted theft of same whilst being worn are rendered impossible since the locking strip 15 must be flexed out by force at the back of the garment and be detached before the pins 11 can swing out.

In the modified construction shown in Figures 6 and 7, the pins have mutually-parallel laterally-extending portions 13 as in the above described construction and have outer portions 19 extending from said portions 13 in perpendicular relation thereto. The locking strip has a median portion 28 of greater width than its end portions 16 so as to be capable of overlying the outer portions 19 of the pins. The end portions 16 of said strip are offset as in the first-described construction to provide transversely-extending shoulders for abutting the portions 13 of the pins.

In the further modification shown in Figures 8 and 9, each of the pins has an inner portion 21 disposed at an angle of inclination with respect to the axis of the hinge 12, and an outer portion 22 disposed in angular relation to said inner portion 21. The locking strip 15 has offset end portions 16 connected to the main part of the strip by obliquely disposed shoulder portions 17 adapted to abut the correspondingly sloping pin portions 21. That is to say, in Figures 8 and 9 the pin 11b is provided with the angular pintle portion 11c fitting in the socket or holding means 12a, and the shank portion of the pin includes

the obliquely disposed portions 21 and 22, the former performing the same function as the cranked portion 13 and the pin in Figures 1 to 7, and the latter having the piercing point at the end thereof.

I claim:

1. Retaining means for articles of ornamental wear, comprising, the combination with the article, of a pair of garment piercing pins each including a shank portion and an angularly disposed pintle at one end, means on the back of the article for pivotally supporting said pintles, and said shank portions each including a garment piercing arm and a cranked portion laterally spaced from and joining said pintle, and a combined pin guard and locking strip having end portions formed to engage beneath the cranked portions of the pin and also provided with shoulders to engage the cranked portions of the pin while the intermediate portion of the strip overlies and conceals the garment piercing arm portions and the points of the pins.

2. Retaining means for badges, brooches, bars for decorative ribbons or like articles, comprising, a pair of spaced apart pins each including a shank and a pintle, means for hingedly mounting said pintle on the back of the article, and each of said pins having the inner end of its shank portion permanently cranked laterally to the plane of movement about the pintle, said cranked portion being spaced from the pintle, and said pins being adapted, when swung away from said article, to be passed through a garment or the like and thereafter to be swung down towards the back of said article, and a springy locking strip having shoulders in the proximity of its ends and which is so formed that by flexing said strip to bowed form and then releasing the same, end portions of said strip beyond the shoulders are adapted, as the strip straightens, to engage beneath the said permanently cranked and laterally extending portions of said pins while the intermediate portion of said strip overlies the shank portions of the pins, the shoulders of the locking strip providing endwise location for said strip in conjunction with the laterally extending portions of the cranked pins.

3. Retaining means for badges, brooches, bars for decorative ribbons or like articles according to claim 2, wherein the locking strip is formed with offset end portions providing said shoulders adapted, by abutting the permanently cranked laterally extending portions of the pins to locate the said locking strip against endwise displacement when in locking position.

4. A retaining means for badges, brooches, bars for decorative ribbons or like articles according to claim 2, wherein the pins are formed to provide laterally-extending portions each parallel to the hinge axis beneath which end portions of the locking strip are adapted to engage, and with outer portions which are disposed each at an acute angle with respect to the associated laterally-extending portion, the locking strip being substantially parallel sided and extending in a straight line from one pin to the other, and having transverse shoulders for abutting said laterally-extending portions of the pins.

5. A retaining means for badges, brooches, bars for decorative ribbons or like articles according to claim 2, wherein the pins are formed to provide laterally-extending portions each parallel to the hinge axis and beneath which end portions of the locking strip are adapted to engage, and with

outer portions extending substantially perpendicular to said laterally-extending portions, and the locking strip has a median portion of greater width than its end portions so as to be capable of overlying the said outer portions of the pins, and has transverse shoulders for abutting the laterally-extending portions of the pins.

6. A retaining means for badges, brooches, bars for decorative ribbons or like articles according to claim 2, wherein each pin has an inner portion disposed at an angle of inclination with respect to the hinge axis of the pin, and an outer portion

disposed in angular relation to said inner portion, and the locking strip is formed to extend in a straight line from one pin to the other and has obliquely disposed shoulders for abutting the said inner portions of the pins.

7. A retaining means for badges, brooches, bars for decorative ribbons or like articles according to claim 2, wherein the locking strip has a natural bowed form and the end portions thereof are offset on the salient side of its curvature to provide shoulders for abutting the pins.

ARTHUR WAKEFIELD MADGER.
